INVENTOR.

BY Richard B. Queen

ATTORNEY.

UNITED STATES PATENT OFFICE.

JOHN B. SALTERINI, OF NEW YORK, N. Y.

DESIGN FOR A LAMP ARM.

Application filed June 18, 1927. Serial No. 22,494. Term of patent 3½ years.

To all whom it may concern:

Be it known that I, JOHN B. SALTERINI, a citizen of the United States, residing at New York, in the county of New York and State of New York, have invented a new, original, and ornamental Design for a Lamp Arm, of which the following is a specification, reference being had to the accompanying drawing, forming a part thereof.

I claim:

The ornamental design for a lamp arm as shown.

J. B. SALTERINI.
